COMBINED VEHICLE GRILLE AND HEAD LAMP GUARD

Frank J. Faulhaber, New York, N.Y.

Application January 29, 1958, Serial No. 49,438

Term of patent 7 years

(Cl. D14—18)

FIG. 1

The characteristic features of my design for the combined article disclosed resides in the head lamp guard members disposed on the sides having the configuration shown.

I claim:

The ornamental design for a combined vehicle grille and head lamp guard, substantially as shown and described.
